DESIGN FOR A COMBINED DESK MICRO- PHONE AND LOUD-SPEAKER

William J. O'Neil, Atlantic Beach, N. Y., assignor to Dictaphone Corporation, New York, N. Y., a corporation of New York

Application March 13, 1942, Serial No. 106,194

Term of patent 14 years

To all whom it may concern:

Be it known that I, William J. O'Neil, a citizen of the United States and a resident of Atlantic Beach, in the county of Nassau and the State of New York, have invented a new, original, and ornamental Design for a Combined Desk Microphone and Loud Speaker, of which the following is the specification, reference being had to the accompanying drawing, forming part thereof.

Figure 1 is a perspective view of the right end and front of a combined desk microphone and loud speaker, showing my new design. Figure 2 is a rear elevational view, and Figure 3 a side elevational view thereof.

I claim:

The ornamental design for a combined desk microphone and loud speaker, substantially as shown.

WILLIAM J. O'NEIL.
